UNITED STATES PATENT OFFICE.

AXEL OLSON AND ALFRED HAST, OF ST. PAUL, MINNESOTA; SAID HAST ASSIGNOR TO
SAID OLSON.

KNIFE SHARPENER.

Application filed April 17, 1922. Serial No. 554,312.

To all whom it may concern:

Be it known that we, AXEL OLSON and ALFRED HAST, subjects of the King of Sweden, residing at St. Paul, in the county of 5 Ramsey and State of Minnesota, have invented certain new and useful Improvements in Knife Sharpeners, of which the following is a specification.

This invention relates to knife sharpeners, and more particularly to that type of sharpeners wherein the sharpening medium consists of a pair of co-operating rotary disks, an object of the invention being the provision of a device of the class described 10 having steel disks which are harder than the object to be sharpened, and which is constructed with adjusting means whereby the disks may be minutely adjusted to maintain an exact contacting relation between them.

20 A further object of the invention is the provision of means, in a device of the class described, wherein the disks are readily interchangeable for the purpose of distributing the wear thereon, so that both flat faces 25 of the disks may be utilized.

To these and other ends the invention consists in the construction, combination and arrangement of parts hereinafter described and claimed.

30 In the accompanying drawings, forming part of this specification:

Figure 1, is a perspective view of our invention partly broken away.

Fig. 2, is a plan view of our improved 35 sharpener.

Fig. 3, is a side elevation of Fig. 2.

Fig. 4, is a perspective view of one of the wheel supporting standards or posts.

Fig. 5, is a sectional view on line 5—5 of 40 Fig. 3.

Fig. 6, is a front view of the upper portion of one of the disk supporting posts, and

Fig. 7, is a fragmentary view of the center of the disks.

45 In the drawings 1 designates a base, the edges 2 and 3 thereof being preferably at right angles to each other, said edges being joined at their outer ends to the preferably outwardly curved edge 4, whereby is formed 50 a triangular base plate.

Preferably integral with the plate is the standard or disk support 5, formed with a boss 6, the face 7 thereof preferably parallel with the edge 2 and at right angles to the

flat surface of the base. Centrally, the 55 standard or post is provided with a horizontally disposed tapped opening 8 extending parallel with the edge 3 and top surface of the base.

Arranged concentrical with the opening 8, 60 and extending inwardly from the face of the boss is the ring 9, preferably rectangular in cross section, the inner diameter of the ring being somewhat larger than the tapped opening 8, and the outer diameter thereof 65 being somewhat smaller than the diameter of the boss.

Threaded in the tapped opening 8 is the screw 10 formed with an enlarged shank 11, 70 said shank fitting the inner bore of the ring 9, and resting with its shoulder 12 against the bottom of the circular cavity formed by the ring.

The screw is further provided with a disk-like head 13. Rotatable on the shank portion 11, by means of the central bore 14, is the sharpening disk 15, said disk being also provided, on opposite sides, with similar circular recesses 15', said recesses being concentric with the central bore and adapted to fit over the ring 9, so as to journal thereon as is best shown in Figure 5 of the drawing. The disks are made of tool steel tempered to a hardness exceeding that of ordinary cutlery, so that the hard metal will abrade 80 or shave the knife edge and thereby sharpen it. Thus, the disk may be reversed so as to present either of its flat faces inwardly, the recesses 15' serving as a counter-sink for the head 13 of the screw. The edge 3 of the base is cut away intermediate its ends to form a slideway or seat 15" for the movable disk supporting post 16. The sides 16' of the seat extend inwardly at right angles to the edge 3 and the bottom 16" thereof extends parallel with the edge 3. The side walls 16' incline or lean in parallelism 90 slightly away from the disk 15.

Centrally the bottom 16" of the seat is formed with a tapped opening 17 extending 100 parallel with the screw of the post 16'. The lower end of the post 16 fits slidably in the slideway 15", the post being suitably crooked to bring its upper portion perpendicular to the base. The post is further provided with an elongated opening 17' adapted to freely receive the screw 17" which threaded- 105 ly engages the opening 17 in the base. The

post may thus be firmly secured in the seat, it being obvious that a vertical sliding movement thereof will change its relative position with respect to the post 5. As the angle 5 of inclination of the wall 16' is very slight, a minute adjustment of the relations between the two uprights is had.

The top of the post 16, is an exact duplicate of the top of the standard 5 so that 10 the disks 15 may be interchanged from one post to the other.

The disks are exact counter-parts of each other, one disk running with its periphery immediately adjacent the flat face of the 15 other, the standard being disposed on the base plate accordingly to permit this arrangement. As it is very difficult to mount a pair of disks in accurate relation so as to secure an even rolling contact between 20 them, and as an exact rolling contact is desirable to secure positive action of one disk upon the other to secure a turning movement of both, and thus secure efficient sharpening results, we have found it necessary to 25 have an adjustment whereby the disk may be minutely adjusted as by means of the structure described in the foregoing. By making the disks interchangeable as described, both flat faces of the disks are available for use 30 as well as the peripheries thereof, thereby materially extending the usefulness of the device and the intervals for renewal of disks. It will be noted that by mounting one disk to have its outer side flush with the periphery of the other the points of contact between the cutting edge of the knife and the 35 two inner peripheral edges of the disks are appreciably separated, as distinguished from rollers where the two peripheral corners are contiguous and the knife is drawn diagonally between them. In other words, the point at which the shaving is being cut from one side of the cutting edge of the knife is spaced longitudinally a 40 distance equal to the full thickness of either disk thereof, from point at which the shaving is being cut on the opposite side of the knife edge. The advantage of thus having these points spaced an appreciable distance 45 from one another, enables the operator to slightly move the knife laterally in a sharpening operation to thus secure a leverage tending to separate the wheels and thereby 50 secure a relatively heavy pressure against the cutting edges of the wheels concurrently with a drawing movement of the knife over the same. We have found that this enables 55 the corners of the disks to take a better hold on the steel for removing an unbroken shaving therefrom.

In Figure 3, *a* designates a knife blade, the cutting edge thereof being here shown wedged between the periphery of one and the face of the other disk, and being drawn 60 toward the user as indicated by the arrows

in Figure 1, wherein the knife is indicated in dotted lines. Thus, the disks abrade the knife edge simultaneously on opposite sides.

When the knife is pushed away from the user in a return stroke, the outer corner of that disk which rolls on the side of the other, and the inner corner of the disk upon whose side the first named disk rolls, will shave the cutting edge of the knife on opposite sides simultaneously and thus effect 75 a sharp edge. When the user draws the knife in a direction intersecting the ninety degree angle between the inner faces of both disks, then the inner circular corner of that disk rolling on the side of the other, will shave one side of the cutting edge, and the inner corner of the disk whose side is rolled upon, will shave the other side of the cutting edge of the knife with its inner peripheral corner. It will be noted, that when the knife 80 is drawn in a diagonal direction, as just described, the points on the edge of the knife acted upon simultaneously by the two disks are appreciably separated, which separation 85 is due to the mounting of the disks so that one will roll on the side of the other. Further, when the knife is drawn over the disks in a sharpening operation, especially in a diagonal direction, the disks are engaged at a point located on a level a trifle above their 90 centers of rotation, thus causing the down pressure on the knife exerted by the user to rotate the disks slightly concurrently with a sharpening movement, and thus place a new cutting portion of the peripheral corners of the respective disks in play.

We claim:

1. In a device for sharpening knives, in combination, a base, a pair of steel disks each of uniform diameter and having flat sides to form peripheral knife sharpening corners at the juncture of the periphery with said sides, said disks being mounted and arranged on said base to be normally rotatable, respectively, in vertical planes at right angles to each other, and have the inner peripheral knife sharpening corner of one disk flush with the outer peripheral knife sharpening corner of the other disk, the mounting of said disks including a supporting post for each disk located respectively on the outer side of each of said disks.

2. In a device for sharpening knives, a base, a pair of metallic disks rotatably mounted on said base to rotate respectively in vertical planes at right angles to each other, so that the periphery of one disk will roll on the face of the other disk at a point close to the outer edge of the latter, the mounting of said disks including an adjustable support for that disk which rolls on the other, said support being adjustably movable in a vertical plane in a diagonal direction relative to the other disk.

3. In a device for sharpening knives, a

base, a pair of sharpening disks rotatably mounted on said base to rotate respectively in vertical planes at right angles to each other, so that the periphery of one disk will 5 roll on the face of the other disk at a point close to the outer edge of the latter, the mounting of said disks comprising a supporting post for each disk, each post having a readily removable outwardly extending 10 bearing member for rotatably supporting its respective disk, said bearing member having a disk-shaped head, at its outer free end, and a counter sunk cavity to wholly receive said disk-shaped head in either side of 15 each of said disks to thereby render the disks reversible.

4. In a device for sharpening knives, a base, a pair of metallic disks rotatably mounted on said base to rotate respectively

in vertical planes at right angles to each other, so that the periphery of one disk will roll on the face of the other disk at a point close to the outer edge of the latter, the mounting of said disk comprising a supporting post for each disk, each post having a readily removable outwardly extending bearing member for rotatably supporting its respective disk, a concentric recess in opposite faces of each disk, a head on each of 20 said bearing members fitting in the outer 25 recess of their respective disks, and a ring carried by each support surrounding its bearing member and fitting into the inner 30 recess of their respective disks.

In testimony whereof we affix our signatures. 35

AXEL OLSON.
ALFRED HAST.
